UNITED STATES PATENT OFFICE.

ELIJAH FLEET WEES, OF KENOVA, WEST VIRGINIA.

RUDDER.

Application filed December 8, 1926. Serial No. 153,395.

This invention relates to the steering of boats and more particularly to the type designed for towing, whereby their steering capacity is increased, by the provision of a 5 rudder presenting a large water engaging surface and including an auxiliary blade which, when lowered, increases the depth and extent of surface of the rudder, said blade being adjustable vertically to enable 10 the rudder to clear sand bars and the beds of shallow bodies of water.

The invention provides an adjustable rudder embodying main and auxiliary blades combined in a novel manner and actuating 15 means mounted upon and associated with the rudder members or blades to admit of the depth of the rudder being varied or adjusted as occasion may require.

While the drawings illustrate a preferred 20 embodiment of the invention, it is to be understood that in adapting the means to meet specific needs and requirements, the design may be varied and such other changes in the minor details of construction may be resort- 25 ed to within the scope of the invention as claimed, without departing from the spirit thereof.

For a full understanding of the invention 30 and the merits thereof reference is to be had to the following description and the drawings hereto attached, in which:

Figure 1 is a side view of the stern portion of a boat provided with an adjustable rudder embodying the invention.

Figure 2 is a view similar to Figure 1, having the main blade or member of the rudder and the rudder post in section.

Figure 3 is a horizontal sectional view of the rudder, on the line 3—3 of Figure 2.

Figure 4 is an enlarged sectional view on the line 4—4 of Figure 1, looking rearward, as designated by the arrows, and showing means for utilizing steam or other fluid medium for operating the adjustable blade or member of the rudder.

Figure 5 is a detail sectional view showing means for operating the adjustable rudder member or blade electrically.

Corresponding and like parts are referred 50 to in the following description and designated in the several views of the drawings by like reference characters.

The numeral 1 designates the hull of a boat and the numeral 2 the stern post to 55 which the rudder is pivotally connected in any usual or preferred way. The rudder

illustrated is of the balanced type, that is, the rudder post 3 is disposed intermediate the front and rear ends of the rudder to equalize the stresses. The main member or 60 blade 4 of the rudder is hollow and open at its bottom to receive the auxiliary or adjustable member or blade 5, which is provided at its lower or bottom edge with a shoe 6 which projects laterally from opposite sides 65 of the rudder. The blade 5 has a snug fit within the blade or member 4, as indicated most clearly in Figures 2 and 4 of the drawings. Vertical slots 7 formed in opposite 70 end portions of the auxiliary blade 5, receive pins 8 supported at their ends in the side walls of the main blade or member 4. The pin and slot connections limit the downward movement of the auxiliary blade and sustain the major portion of the longitudinal 75 stresses, as indicated most clearly in Figure 2 of the drawings. The lower portion of a side wall of the main member or blade 4 is removable, as indicated at 9, thereby admitting of ready access to the interior of 80 the main blade or member for any desired purpose. Bolts or other suitable fastening means 10 are employed for securing the removable part 9 when in place.

The rudder post 3 is hollow and in the 85 form of a cylinder, and receives a stem 11 which is connected at its lower end in any determinate way to the adjustable member or blade 5. The stem 11 extends through the closed ends of the post 3 and receives an 90 open coil spring 12 which is confined between the upper closed end of the post and a stop provided on the stem 11. The spring 12 acts jointly with the weight of the blade 5 to normally hold it projected. A piston 95 14 is fast upon the stem 11 and operates within the post 3 and constitutes an abutment for the lower end of the spring 12.

A cylinder 20 is mounted upon the boiler deck or other convenient part of the boat in 100 line with the hollow post 3 and receives a piston 21 which is fast to the upper end of the stem 11 passing upwardly into the cylinder through the lower end thereof. Pipes 22 and 23 connect opposite ends of the cylinder 20 with a four way valve 24 conveniently positioned and connected to a boiler or compressed air tank by means of a pipe. 25 A fluid medium, such as steam or compressed air, when admitted into the lower 110 end of the cylinder 10 below the piston 21 operates to move said piston upwardly with-

- in the cylinder and to elevate the auxiliary blade or member 5, thereby reducing the draft of the rudder so that it may pass over shallow places without injury thereto. The 5 four-way valve 24 may be of any approved construction and when turned to one position, admits steam or compressed air into the lower end of the cylinder 20 to elevate the auxiliary blade 5 in the manner indicated. 10 When the valve 24 is turned to the opposite position, the piston 21 descends and the auxiliary blade or member 5 automatically lowers and assumes its normal position to admit of the rudder having a maximum draft. 15 The auxiliary blade 5 may be operated in any preferred way and, as indicated in Figure 5, a solenoid 17 is mounted upon the rudder post 3 and the stem 11 passes therethrough and when said solenoid is energized 20 by the passage of a current of electricity therethrough, the stem 11 is attracted, as indicated in said figure, thereby effecting a vertical movement of the auxiliary blade and a withdrawal thereof within the main 25 blade 4. Stops 18, projecting from opposite sides of the rudder, are adapted to engage the sides of the hull 1 and limit the swing of the rudder in each direction. A tiller 19 is shown connected with the rudder post as 30 means for operating the rudder. However, it is to be understood that the rudder may be operated in any usual way generally practiced in the steering of water craft. 35 The lower corners of the blade 5 are rounded to prevent catching trash and to ride over obstructions that may come in contact therewith. Curved straps 26 are located upon opposite sides of the curved ends of the blade 5 and are pivoted at their upper 40 outer ends to the blade 4, at 27, and are formed with longitudinal slots 28 through

which headed fastenings 29 pass to connect them to the shoe 6. These straps 26 constitute fenders and the arrangement is such as to admit of a pivotal movement as the blade 45 5 is elevated and lowered.

Having thus described the invention, what I claim is:

1. A rudder comprising a main hollow member open at its bottom, an auxiliary member having a snug fit within the main member and movable therein through the bottom, a hollow rudder post extending upwardly from the main member, a stem connected to the auxiliary member and passing through the hollow post, and an open coil spring mounted upon the stem and housed within the upper portion of the post and confined between the upper end of said post and a stop carried by the stem and operating to normally hold the auxiliary member projected. 55

2. A rudder comprising a main hollow member open at its bottom, an auxiliary member having a snug fit within the main member and movable therein through the bottom, a hollow rudder post extending upwardly from the main member, a stem connected to the auxiliary member and passing through the hollow post, and an open coil 60 spring mounted upon the stem and housed within the upper portion of the post and confined between the upper end of said post and a stop carried by the stem and operating to normally hold the auxiliary member projected. 65
